CLAIM

The ornamental design for a lamp housing, as shown and described.

DESCRIPTION

FIG. 1 is a front view of the lamp housing according to a first embodiment of the new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front view of the lamp housing according to a second embodiment of the new design;

FIG. 8 is a back view thereof;

FIG. 9 is a left side view thereof;

FIG. 10 is a right side view thereof;

FIG. 11 is a top view thereof; and,

FIG. 12 is a bottom view thereof.

The broken lines depict portions of the lamp housing that form no part of the claimed invention.
